UNITED STATES PATENT OFFICE.

ALBRECHT RÖGGE, OF BERLIN, GERMANY.

BENDING AND STRAIGHTENING MACHINE.

No. 907,889.

Spécification of Letters Patent.

Patented Dec. 29, 1908.

Application filed February 24, 1906. Serial No. 302,735.

To all whom it may concern:

Be it known that I, ALBRECHT RÖGGE, a subject of the King of Prussia, and a resident of Nordhafen 8, Berlin, Germany, have invented a new and useful Improved Bending and Straightening Machine, of which the following is the specification.

The present invention relates to bending machines and straightening machines for rolled-iron and the like.

In the case of hitherto known bending and straightening machines for rolled-iron and the like it has hitherto been necessary to move the tool, such as a straightening stamp, situated opposite the straightening plate or surface-plate by the instrumentality of such elements as permit the working-stroke to be adjusted or to be regulated. This necessity was due to the circumstance that materials of the most various profiles had to be dealt with on one and the same machine. Such adjusting devices, however, cause the machines to be somewhat complicated and moreover in operation they were not reliable to the desired degree.

The present invention relates to a bending and straightening machine in which the tool or the slide for receiving the straightening or bending stamp is set in action as soon as said slide is rigidly connected by means of a cotter or wedge or the like with the end of one or more connecting rods which continuously receive a uniform reciprocating motion by means of an eccentric or other suitable means. Now in order to render the machine provided with such a device for always imparting to the tool a stroke of constant length highly serviceable for materials or work, that is articles to be operated upon, of all possible dimensions, according to the present invention a device for finely adjusting the surface-plate is provided, and consequently the means for adjustment are transferred to that place where the greatest use of them can most suitably be made.

The accompanying drawings illustrate by way of example two embodiments of machines according to the present invention, in the case of each embodiment the same reference characters designating in all figures the same parts.

In said drawings—Figure 1 is a side elevation of one embodiment of a straightening or bending machine according to the present invention, and Fig. 2 is an end elevation

showing the spur-wheel gear of said machine. Fig. 3 is an end elevation of the lower portion of the second embodiment of a machine according to the present invention, while Fig. 4 is a side elevation of the same, and Fig. 5 a plan of the same.

Referring to Figs. 1 and 2, *a* is the base plate which is cast in one piece with the perpendicular sides *b b*. Between the latter and at one side is mounted the spur-wheel gear for driving the straightening stamp arranged displaceably on the other side. *c c* are fast and loose pulleys arranged on the shaft *d* for switching the power on and off. Upon the shaft *d* is mounted the toothed wheel *e* which drives the larger toothed wheel *f* situated on the shaft *g* which carries a second smaller toothed wheel *h* keyed rigidly to it, which wheel *h* transmits the motion which is thus again reduced very much in correspondence with the size of the wheel to two toothed wheels *i j* of equal size mounted on the shafts *k l*. An eccentric *m* is situated centrally on each of said shafts *k l*, the motion of said eccentrics being transmitted by means of eccentric rods *n n* to the slide *o* arranged at the front end of the machine, which slide carries the straightening or bending stamp *p* which is adapted to be adjusted by means of the handle *q*. Said stamp *p* is arranged so as to be capable of being interchanged with other stamps as also are the surface-plates or matrices *r r* which are fixed, for example bolted, on the two fixed sides *b b*. Said surface plates or matrices serve as a resisting support or abutment for the article or work *s* to be bent which in the drawing is represented as an I-beam. The pressure-surfaces or working surfaces of the stamp *p* and of the matrices *r r* lie exactly parallel to one another and at right angles to the motion of the eccentric rods *n n*. In order to avoid the necessity of having to switch off the machine during the forward motion of the work the connection between the eccentric rods *n n* and the slide *o* is not a rigid one, but it is effected by inserting cotters *t* or other suitable members which can be adjusted from the front of the machine suitably by means of two-arm levers *u*. The cotters *t* (shown in Fig. 1) are linked to the levers *u* which are pivoted to the frame of the machine. By drawing the lower ends of the levers *u* off from the machine the cotters are lowered and thereby brought out of contact with the rods *n* and the slide *o*, whereby then the rods *n*

move freely, whereas otherwise the slide is rigidly coupled with said rods. In order to facilitate the forward motion of the work it is advantageous to support the latter upon 5 rollers $v v$ and in order to enable the machine to run uniformly a fly-wheel z is arranged on the free end of the shaft d . The machine enables perfect work exact to a millimeter to be turned out and in consequence of its short 10 compact form enables profile-iron to be bent to circles of about $1\frac{1}{2}$ meters diameter. On the other hand bent profile-iron can be made perfectly straight again.

Referring to the embodiment illustrated 15 in Figs. 3 to 5 this machine is designed especially for somewhat large work. Nevertheless it can be employed for treating small work, though said work cannot be bent to circles of less than 3 meters diameter. The under 20 frame A A of the machine consists of several, in this case three, T-beams extending from one end of the machine to the other, and said frame supports the toothed wheel gears B, C, D, E upon the shafts F G H supported on 25 the sides. Said gear is driven from the belt-pulley I on one end of the shaft F at the other outer end of which the fly-wheel K is keyed. Upon the shaft H is situated an eccentric L the motion of which is transmitted by means 30 of the eccentric rod M to the slide O which is adapted to receive at its front end the bending or straightening tool, that is, the stamp P which is capable of being interchanged with other stamps. The connection between 35 the eccentric rod M and the slide O is in this case also one which is capable of being readily disconnected. The connection is suitably effected by means of the wedge or cotter N which is inserted in slots or longitudinal 40 holes R R in the slide O and the eccentric rod M, and which, for the purpose of undoing the connection, can be withdrawn by means of a lever gearing N'. Also the cotter N is suitably connected with a lever-gearing by 45 which said cotter can be drawn out of the slots R. Thereby the reciprocating rod M finds no resistance in its movement and therefore the slide remains at rest. The surface-plate T stands parallel and opposite 50 to the slide O or the bending stamp P and at right angles to the direction of motion of the

slide, and the work S to be operated upon is placed between said slide or stamp and said surface-plate on rollers U. If the work S is to be bent two suitable matrices T' T², indicated in dotted lines in Fig. 5, are arranged or fixed upon the surface-plate, for example by means of bolts. The surface-plate T can be exactly adjusted by means of the screwed spindles V, V', V², V³, V⁴, V⁵, said spindles 60 being operated from a lever W (Fig. 3) by means of ratchet or like mechanism which in the example shown consists of the ratchet wheels X, X', X², X³, X⁴, X⁵ keyed upon the ends of the screwed spindles and of the pawls 65 Z, Z', Z², Z³, Z⁴, Z⁵ adapted to be actuated by means of the sliding bars W⁴, W⁵ and the links W', W², W³, connecting said sliding bars with the lever W. Now as the motion of all the pawls is exactly the same and also 70 as all the ratchet wheels have exactly the same shape and because on the other hand, the screw threads on the spindles have an extremely small pitch, it follows that the distance of the surface-plate from the working 75 shaft H of the toothed wheel E can be adjusted to the utmost degree of accuracy.

The described arrangement for enabling fine adjustments to be made can be applied 80 to the stamp-plate or surface plate of the machine shown in Figs. 1 and 2. The forward motion of the work can be effected by hand or automatically by means of the machine.

What I claim as my invention and desire to 85 secure by Letters Patent is:—

In a bending and straightening machine the combination of a suitable frame, an anvil supported by said frame, a pair of eccentrics connected by suitable gearing behind said anvil, an adjustable slide opposite said anvil, a pair of eccentric rods connecting said eccentrics and said slide for the purpose of drawing the slide towards the anvil, and keys held by suitable lever gearing in order to disconnect the eccentric rods and the slide. 95

In testimony whereof I have signed my name to this specification in the presence of two subscribing witnesses.

ALBRECHT ROGGE.
